UNITED STATES PATENT OFFICE

133,367

DESIGN FOR A DISPLAY SUPPORT

Paul M. Ressinger, Chicago, Ill.

Application February 21, 1942, Serial No. 105,931

Term of patent 3½ years

To all whom it may concern:

Be it known that I, Paul M. Ressinger, a citizen of the United States, residing at Chicago, in the county of Cook and State of Illinois, have invented a new, original, and ornamental Design for a Display Support, of which the following is a specification, reference being had to the accompanying drawing, forming part thereof.

Fig. 1 is a perspective view of a display support, showing my new design;

Fig. 2 is a front elevational view on a reduced scale; and

Fig. 3 is a side elevational view thereof, also on a reduced scale.

I claim:

The ornamental design for a display support, as shown.

PAUL M. RESSINGER.
